UNITED STATES PATENT OFFICE

2,337,346

ELECTRIC INDUCTION APPARATUS

Justin Peterson, Swampscott, Mass., assignor to
 General Electric Company, a corporation of
 New York

Application February 11, 1942, Serial No. 430,408

6 Claims. (Cl. 171—119)

This invention relates to induction electric apparatus and to movable coil constant current transformers and reactors. Constant current electrical apparatus of this type consists of relatively movable windings and a core providing a magnetic circuit inductively relating the windings, the magnetic repulsion between the windings being a factor in determining the relative positions of the windings at any instant, and hence the current supplied to the load.

In order that the movable windings may respond accurately to changes in current, provision is usually made to prevent the movable windings from binding against the core legs, and it is a practice to provide a guiding means for the movable winding in the form of an arm pivoted at its outer end to an extension of the core clamping structure. Furthermore, the movable winding of the conventional transformer is of such a weight that a counterbalancing means is required for at least partially neutralizing the effect of gravity thereupon. The counterbalancing mechanism in its simplest form usually consists of a fulcrum lever mounted upon the upper end of the magnetic core structure and which is connected to one end by means of a pivot link to the movable coil on the side opposite the pivoted guide arm. Suitably arranged upon the fulcrumed lever is an adjustable weight by means of which the regulation of the transformer may be adjusted. The regulation of such a simple counterbalanced transformer is relatively poor, usually varying within plus or minus several percent, which in the case of a lighting load results in abnormally short lamp life. To improve the regulation of the transformer special precautionary measures must be taken, usually in the form of a relatively complex linkage mechanism between the counterbalancing weight and the movable coil, which includes numerous ball bearings and carefully machined parts together with precision adjusting means. In the event that such a transformer is to be arranged within an insulating liquid filled tank such as may be required for pole mounting, the tank size required is relatively large. The larger the tank, the greater the quantity of insulating liquid required, and the more difficult becomes the mounting problem so that it is extremely desirable to reduce the overall dimensions of such transformers to a minimum.

It is, therefore, an object of the present invention to provide a new and improved electrical apparatus of the movable coil type which requires no mounting brackets for the movable coil nor

any counterbalancing weight and associated lever mechanism.

It is a further object of the present invention to provide a new and improved constant current electrical apparatus of the movable coil type in which the movable coil floats substantially rectilinearly with respect to the stationary coil without the need for any lever or counterweight mechanism to effect partial compensation for the force of gravity acting upon the movable coil.

It is another object of the present invention to provide a new and improved regulating device of the movable coil constant current type in which the movable coil is specially constructed so that the force of magnetic repulsion is greater than the force of gravity acting upon the coil so that no counterbalancing means are required for partially upsetting the force of gravity acting thereupon.

It is a further object of the present invention to provide a new and improved current regulating arrangement for an electric apparatus of the movable coil type.

For a consideration of what I believe to be novel and my invention, attention is directed to the following description and the claims appended thereto taken in connection with the accompanying drawing.

In the drawing Fig. 1 is a side elevation of a constant current transformer constructed in accordance with one form of the invention; Fig. 2 is a set of curves illustrating regulation characteristics which will be employed in describing my invention, and Fig. 3 diagrammatically illustrates a constant current electric apparatus which is provided with my improved current regulating arrangement.

Referring to the drawing, the constant current transformer comprises a magnetic core structure having a winding leg 10 and a pair of outer legs 11 which cooperate to define a pair of windows within which are arranged the primary and secondary winding coils 12 and 13 surrounding the winding leg 10. The primary winding 12 is fixedly arranged in the lower end of the window while the secondary winding 13 is movably arranged thereabove for substantially rectilinear movement in the vertical direction parallel with the sides of the winding leg 10. It is, of course, to be understood that either the primary or secondary winding may be movable. By virtue of the fact that the secondary winding 13 moves vertically up and down in a straight line instead of in an arcuate path, as in the case of the usual trans-

formers in which the secondary winding is supported upon a hinged bracket arm, the opening through the center of the winding coil may be round instead of oblong as is required in the case of the pivotally supported windings. Thus a saving in the overall dimensions of the transformer is effected.

In the usual constant current transformer the force of gravity acting upon the moving coil is considerably greater than the force of repulsion resulting from the currents flowing through the two windings. This is true even in the case of transformers immersed in oil in which instance the buoyancy effect of the oil upon the movable winding is appreciable. This latter effect, however, is still not sufficient to eliminate the necessity for a counterweight and balancing lever even in the case of machines having a 50 per cent reactance and with a cross section of copper adequate to obtain satisfactory cooling with non-circulating oil.

In the case of the present invention the moving coil is so designed and has such mechanical and electrical characteristics that the force of repulsion plus the buoyancy of the oil is greater than the weight of the movable coil assembly. For this purpose the movable coil may be wound of any suitable material, such as aluminum wire or, should it be desired to use copper wire, suitable floats (not shown) may be attached to the upper surface of the movable coil. In the case of the aluminum wound coil, notwithstanding the fact that a greater cross section of conductor is required over that in the case of a copper conductor due to the less favorable conductivity of aluminum, the force of repulsion plus the buoyancy of the fluid is amply sufficient to overcome the force of gravity.

In order to assure that the secondary winding will not bind against the sides of the winding leg or the adjacent faces of the outer leg and will be maintained in a spaced relation therefrom, suitable means may be provided for guiding the movement of the coil between its upper and lower limits of travel. A pair of guide rods 14 are provided, one on each of the opposite sides of the assembly, one being shown in Fig. 1, which guide rods are secured at their upper and lower ends to bracket arms 15 and 16 extending outwardly from the upper and lower portions of the core structure, respectively. The secondary winding is clamped between suitable upper and lower clamping members 17 and 18, respectively, through bolts 19. Rollers 20 and 21 suitably secured to the upper and lower coil clamps 17 and 18, respectively, are adapted to engage with the guide rods 14 to maintain the secondary coil 13 properly spaced within the core window. The rollers 20 and 21 are provided with grooved faces for cooperatively fitting around the vertical guide rods and thus determining the path of movement for the coil. It is to be understood, however, that the movable coil may be allowed to move without guide rollers so that it may wobble slightly, and still a substantially rectilinear movement will obtain.

A transformer constructed as described above has a regulation characteristic as is indicated by the curve 30 of Fig. 2. It will be seen that this characteristic is very flat up to about one-half load, and it droops slightly from there to full load. This drooping may be due to a proximity effect when the coils approach each other as it has been observed that as the coils approach

each other the force of repulsion tends to increase for a given current.

In case a characteristic is desired which is even flatter than that of curve 30 of Fig. 2, this variation in the repulsive force between the two coils may be counteracted by a compensating means which includes an electromagnetic arrangement having a solenoid winding 31 which is mounted upon the upper end of the magnetic core structure and connected in series with the secondary winding 13 through conductors 32, 33, 34, and a suitable load such as lamps 35, as will be seen in Fig. 3. The compensator solenoid winding is hollow and is vertically arranged, preferably coaxially with the primary and secondary windings, and is suitably anchored to the upper core clamping structure. A solenoid core comprising a central leg 36 and a pair of outer legs 37 connected together by an upper yoke portion is supported above the solenoid by means of a suitable yoke bracket 38, the legs of which straddle the upper yoke of the transformer core structure and the lower ends of which legs being secured to the upper clamping member 17 of the secondary coil by a bolt 44. The central leg 36 of the solenoid core is substantially centrally aligned with the opening in the solenoid coil 31 so that it may move freely in and out without frictional engagement therewith as the secondary winding moves.

Since the solenoid coil 31 is connected in series with the secondary circuit and will have substantially constant current flowing therethrough, the magnetic flux on the solenoid core will increase as the core is inserted deeper into the coil. In this manner the movable coil will be biased towards the stationary coil by a force which is a function of or inversely proportional to the spacing between the windings. Thus, the increasing pull of the solenoid offsets the increasing repulsion as the moving coil approaches the stationary coil, and the secondary current may be held practically constant, as is illustrated by curve 40 of Fig. 3.

To adjust the particular value of secondary current which is to be held constant by the device, an adjustable weight 41 consisting of a plurality of shims may be provided such as upon a bolt 42 extending from the upper portion of the solenoid core supporting bracket 38. Also the regulation of the transformer may be varied by providing a movable tap 43 for the solenoid coil 31 which will vary the range of the force due to the solenoid.

Thus, it will be seen that a transformer constructed as described above is relatively compact in design and comprises relatively few moving parts, and is characterized by a complete absence of pivoted levers, connecting linkages and the like. By the elimination of such levers and linkages, the overall dimensions are practically reduced to the dimensions of the core and coil units so that a reduction may be made in the size of the tank or enclosure provided for closing the device. Corresponding savings in the amount of oil and overall weight of the unit are effected and which lessen the problem of mounting such a device on poles.

Although I have shown and described particular embodiments of my invention, I do not desire to be limited to the particular embodiments described, and I intend in the appended claims to cover all modifications which do not depart from the spirit and scope of my invention.

What I claim as new and desire to secure by Letters Patent of the United States is:

1. In a constant current electrical apparatus, the combination of a magnetic core having a winding leg, of a plurality of windings surrounding said leg, one of said windings being adapted to move longitudinally along said leg in response to reaction between the currents flowing through said windings, and electromagnetic means for exerting a biasing force against said movable winding, said biasing force being a function of the spacing between said windings.

2. In a constant current transformer, the combination with a magnetic core having a substantially rectilinear winding leg and cooperating members forming a window, of a plurality of windings surrounding said leg, one of said windings being adapted to move substantially longitudinally of said leg in response to reaction between the currents flowing through said windings, and electromagnetic means exerting a force against said winding tending to prevent movement of said movable winding with respect to the other of said windings, said biasing force being greater the nearer said movable winding is to the second of said windings.

3. In a constant current transformer, the combination of a magnetic core having a substantially rectilinear winding leg, said winding leg being vertically disposed, a plurality of windings surrounding said leg, one of said windings being adapted to move vertically along said leg in response to current reaction between said windings, and electromagnetic means exerting a biasing force against said movable winding tending to prevent separation of said windings, said biasing force being greater in accordance with the proximity of said windings relative to each other, said biasing force being of such magnitude as to effect a substantially constant current regulation for said transformer.

4. In a constant current transformer, the combination with a magnetic core having a substantially rectilinear winding leg and cooperating members forming a window, a primary winding surrounding said winding leg, a secondary

winding surrounding said leg above said primary winding and adapted to move relative to said primary winding in response to reaction between the currents flowing through said windings, a solenoid supported on said magnetic core and connected in series with said secondary winding, and a magnetic core movable with said secondary winding and having a portion magnetically associated with said solenoid, a coupling between said core and said solenoid varying in accordance with the spacing between said windings.

5. In a constant current transformer, the combination with a magnetic core having a substantially rectilinear winding leg disposed in a substantially vertical position and cooperating members forming a window, a primary winding surrounding said winding leg, a secondary winding surrounding said leg above said primary winding and adapted to move relative to said primary winding in response to reaction between the currents flowing through said windings, means secured to said magnetic core for guiding the movement of said secondary winding in a vertical direction substantially parallel with and in a spaced relation with respect to said winding leg, a solenoid supported on said magnetic core and connected in a series with said secondary winding, and a magnetic core movable with said secondary winding and having a portion magnetically associated with said solenoid, a coupling between said core and said solenoid varying in accordance with the spacing between said windings.

6. In a constant current electrical apparatus, the combination of a magnetic core having a winding leg, of a plurality of windings surrounding said leg, one of said windings being adapted to move longitudinally along said leg in response to reaction between the currents flowing through said winding, and electromagnetic means for exerting a biasing force against said movable winding being a function of the spacing between said windings, and means for varying the range of said biasing force.
